DESIGN FOR A MILKING PARLOR STALL

Howard J. Ferris, Harvard, Ill.

Application December 12, 1932. Serial No. 46,439

Term of patent 14 years

To all whom it may concern:

Be it known that I, HOWARD J. FERRIS, a citizen of the United States, residing at Harvard, in the county of McHenry and State of Illinois, have invented a new, original, and ornamental Design for Milking Parlor Stalls, of which the following is a specification, reference being had to the accompanying drawing forming part thereof.

Figure 1 is a perspective view of the milking parlor stall;

Fig. 2 is a top plan view of the same somewhat reduced; and

Figure 3 is a front view showing my new design.

I claim:

The ornamental design for a milking parlor stall, as shown.

HOWARD J. FERRIS.
